UNITED STATES PATENT OFFICE.

HERMANN A. EIBACH, OF ROCKFORD, ILLINOIS.

DESIGN FOR A TOE-CLIP FOR BICYCLES.

SPECIFICATION forming part of Design No. 26,336, dated November 24, 1896.

Application filed March 16, 1896. Serial No. 586,485. Term of patent 7 years.

To all whom it may concern:

Be it known that I, HERMANN A. EIBACH, a citizen of the United States, residing at Rockford, in the county of Winnebago and State of Illinois, have invented and produced a new and original Design for Toe-Clips for Bicycle-Treadles, of which the following is a specification, reference being had to the accompanying drawings, forming a part thereof.

In the drawings, Figure 1 is an isometrical view of my toe-clip. Figs. 2 and 3 are sections at the dotted lines X.X and X'X' in Fig. 1.

A toe-clip embodying my invention is of hook form, having its stem bent at right an-

gles to form an attaching-lug and having longitudinally-extending corrugations commencing near the hook end and extending to a point about half-way up the stem of the hook, forming a central flute on the inner face of the hook.

What I claim is—

The design for a toe-clip for bicycle-treadles herein shown and described.

HERMANN A. EIBACH.
